UNITED STATES PATENT OFFICE.

HARTLEY O. BAKER AND CARLETON A. ORR, OF PUEBLO, COLORADO, ASSIGNORS TO THE BAKER STEAM MOTOR CAR AND MANUFACTURING CO., INC., OF PUEBLO, COLORADO.

WATER-TUBE BOILER.

Application filed November 14, 1919. Serial No. 338,038.

To all whom it may concern:

Be it known that we, HARTLEY O. BAKER and CARLETON A. ORR, citizens of the United States, residing at Pueblo, in the 5 county of Pueblo and State of Colorado, have invented certain new and useful Improvements in Water-Tube Boilers; and we do hereby declare the following to be a full, clear, and exact description of the invention, such as will enable others skilled in the art to which it appertains to make and use the same.

This invention relates to water tube boilers or steam generators of the semi-flash 15 type, and is an improvement over the boilers disclosed in the copending applications, Serial Nos. 269,432, and 286,002, filed Jan. 3, 1919 and March 29, 1919, respectively, which have matured into Patents Numbers 20 1,409,515 and 1,425,162, respectively.

The primary object of the invention is the provision of a water tube boiler or steam generator composed of tubes or piping so arranged as to afford maximum efficiency, and the construction being such that the tubing can be electrically and autogenously welded, making a compact integral unit without screw threads or expanded joints, and capable of withstanding 25 high working pressures (five hundred to seven hundred pound per square inch) with a high factor of safety.

Another object is the novel arrangement of the tubing for efficiently heating the 35 water and generating or flashing it into steam, the steam being held in reserve in a large quantity to suit the varying needs of the engine, and the construction providing for the heating of the steam held in reserve 40 and the superheating of the steam as it is delivered.

A further object is the provision of such a boiler having novel means for effecting the separation of the steam and water, to 45 avoid particles of water passing with the steam into the steam coils, and in this connection it is an object of the invention to equalize the pressure in the tubing, so that the water will remain at the bottom and will 50 not flow under accumulating pressure of the steam into the steam coils.

A still further object is the provision of

a novel arrangement and construction of the several coils of the boiler, and their relation with one another, whereby to obtain a 55 compact and strong construction, which will be efficient in operation and capable of a high rate of steam production under high pressure.

With the foregoing and other objects in 60 view, which will be apparent as the description proceeds, the invention resides in the construction and arrangement of parts hereinafter described and claimed, it being understood that changes can be made within 65 the scope of what is claimed without departing from the spirit of the invention.

The invention is illustrated in the accompanying drawings, wherein:—

Fig. 1 is a side elevation of the boiler, 70 portions being broken away.

Fig. 2 is a section on the line 2—2 of Fig. 1.

Fig. 3 is an elevation of the central stand pipe or drum. 75

Fig. 4 is a section on the line 4—4 of Fig. 3.

Fig. 5 is a section on the line 5—5 of Fig. 1.

Fig. 6 is a cross section on the line 6—6 of Fig. 4. 80

Fig. 7 is a plan view of the superheater coils.

Fig. 8 is an elevation of the superheater coils, portions being broken away and shown 85 in section.

Fig. 9 is a fragmentary elevation showing the connections provided for a blow off and level indicator and automatic water control. 90

Fig. 10 is an elevation of a modified form of stand pipe or drum.

Fig. 11 is a central vertical section of the stand pipe or drum shown in Fig. 10.

Fig. 12 is a cross section on the line 2—2 of Fig. 11. 95

A vertical stand pipe or drum 1 is located at the center of the boiler and constitutes a core around which the tubing and coils are located. Surrounding the upper end portion of the drum 1 is a set of superposed spiral coils 2 of metal tubing, and these coils are connected alternately at their inner and outer ends, so as to be continuous, 100

and the water is delivered through the water supply pipe 3 which is connected to the upper end of the coils 2, for the downward flow of the water through said coils, alternating outwardly and inwardly in the coils as the water flows through the coils in succession. These coils 2 are "economizer" coils, being located at the top whereby the water in entering the boiler will receive its initial heat, the products of combustion after passing the generating and superheating coils heating the "economizer" coils 2, thereby utilizing the remaining heat for raising the temperature of the water before passing to the generating coils. A delivery pipe 4 extends upwardly from the lower end of the coils 2, within said coils at one side of the drum 1, and has a downwardly extending leg or nozzle 5 leading downwardly through the upper end of the drum and within the drum to a point near the lower end thereof, thereby delivering the water into the lower portion of the drum from the economizer coils. The water is thus admitted into the lower portion of the drum after passing through the coils 2, and the water passes from the lower end of the drum through a pipe 6 leading from the lower end of the drum radially to one side to the lower end of a vertical stand pipe 7 disposed at one side of the coils parallel with the central drum 1. The pipe 6 and stand pipe 7 are preferably of tubing of considerably larger diameter than the spiral coils surrounding the drum. A branch 8 extends outwardly from the juncture of the pipes 6 and 7 and has a depending nipple 9. This branch 8 provides a trap or pocket for collecting sediment, scale accumulations and other foreign matter, which can be blown off through the nipple 9 to which a suitable blow off valve can be attached. Thus, any sediment or accumulation within the drum 1 into which the coils discharge, will pass downwardly through the pipe 6 and into the trap 8, as well as from the stand pipe 7, enabling the sediment and accumulation to be discharged from time to time. The trap or branch 8 also has a pair of upwardly diverging nipples or pipes 10 to which can be connected a water level indicator and an automatic feed water control (not shown) for enabling the water level to be indicated and regulated by devices which need not be illustrated or described herein. The trap 8 thus serves as a means for collecting and blowing off the sediment, as well as providing means for the connection of the indicator and control.

Spiral generating coils 11 surround the lower portion of the drum 1, being superposed, and the alternate coils extend in opposite directions. These coils are of tubing of about the same diameter as the coils 2, but it is preferable to have the lowermost coil 11 of slightly larger tubing. The outer

ends of the coils 11 are secured to opposite sides of the stand pipe 7, and, as shown in Fig. 2, enter said stand pipe, it being well to mention here that the tubing and pipes are all secured together by welding so as to constitute a unitary integral structure. The coils 11 that enter and are secured to the stand pipe 7 are in staggered relation as seen in Fig. 2, and the inner ends of the coils 11 extend upwardly, as at 12, from the planes of the coils and are secured to the side wall of the drum 1. The water which passes from the drum 1 through the pipe 6 up into the stand pipe 7, thus flows into the coils 11 and inwardly therein in reverse spiral paths, and the water is again returned into the drum from the coils 11, thus completing the generating circuit, the water within the lower portion of the drum and coils 11 being immediately above the flames and subjected to the maximum heat for generating the water into steam. The coils 11 are connected to the stand pipe 7 similar to the relation between the ribs of the human body to the back bone, the stand pipe 7 being the "back bone" of the coils and pipes connected thereto.

In order to facilitate the separation from the water which enters the drum from the coils 11, a vertical arcuate baffle plate 13 is disposed within the drum across the inner discharge ends of the coils 11, and vertical partitions 14 are provided between said baffle plate 13 and the wall of the drum to direct the water and steam vertically. A deflector 15 is carried by the wall of the drum and is curved upwardly over the upper end of the baffle plate 13 and downwardly at the inner side of said baffle plate, whereby the water and steam in passing upwardly within the vertical passage between the plate 13 and wall of the drum 1 will strike the deflector 15, which directs the water and steam over the upper end of the plate 13. The deflector 15 will direct the water downwardly, while the steam will turn around the edge of the deflector and pass upwardly into the upper steam chamber within the drum, thereby efficiently separating the steam from the water. This separator (baffle plate 13 and deflector 15) thus separates the water and steam when they are delivered back into the drum, the lower end of the separator or separating space being open so that the water can pass downwardly from behind the baffle plate 13 into the lower end of the water chamber of the drum. Without the provision of the separator it would be possible for particles of moisture to pass up with the steam in the drum, so that the separator reduces to a minimum the saturation of the steam with moisture.

A steam delivery pipe 16 is connected to the upper end of the drum for conducting

245

1,550,942

3

the steam therefrom and extends radially to a point above the stand pipe 7 and the discharge terminal of the pipe 16 extends downwardly at an angle into the stand pipe 5. The steam is thus discharged downwardly into the stand pipe to the lower portion in which the water is held for passage into the generating coils 11, so that any particles of water carried with the steam from the 10 drum will be directed down into the water into the stand pipe 7. This results in the separation of any stray particles of water from the steam, and, furthermore, the pipe 16 in connecting the upper portions of the 15 drum 1 and stand pipe 7 will equalize the pressures therein, so that the water level in the drum 1, stand pipe 7 and coils 11 will be the same. This avoids forcing the water on beyond the tubing provided for 20 it into the steam coils, and any tendency for the pressure to force the water in one direction or the other is balanced by an equal pressure at the opposite end.

Located above the generating coils 11 and 25 surrounding the other spiral coils above said coils 11 are steam reserve or storage coils forming a surrounding chamber or jacket. These coils, which also serve as separating mediums, comprise semi-circular or arcuate 30 pipes 17 of relatively large diameter connected at one end to opposite sides of the stand pipe 7 above the coils 11, whereby to receive the steam from the upper steam space of said stand pipe, and the other ends 35 of the pipes 17 are connected to the opposite sides of a vertical steam header or pipe 18 located diametrically opposite to the stand pipe 7 above the coils 11 and at one side of the coils 2. The pipe 17 resemble ribs 40 connected to the "back bone" stand pipe 7 and extending around the spiral coils and connected to the vertical header 18 into which the steam is delivered. These pipes 17 are on an incline with their lower ends 45 connected to the stand pipe 7, whereby any water carried into the pipes 17 or formed therein by condensation, will drain back into the stand pipe 7, thus resulting in a further separation of the water from the steam 50 as the steam passes from the stand pipe around through the pipes 17 into the header 18.

A steam pipe 19 extends through the upper end of the header 18, and has intake 55 branches 20 extending within the discharge ends of the two uppermost pipes 17, and the branches 20 have slits 21 for admitting the dry steam, thereby excluding water. The upper portion of the stand pipe 7, 60 with the pipe 17 and header 18, provide a storage chamber for steam, whereby to hold a considerable quantity of steam in reserve, sufficient for the varying needs of the engine or other device supplied by the boiler. This 65 reserve steam is kept heated and dry, the moisture flowing down the pipes 17 back into the stand pipe 7, and the branches 20 of the pipe 19 only receive dry steam. The throttle valve 22 is disposed in the pipe 19 for controlling the discharge of steam, being located in the steam circuit between the storage or reserve coils and the superheating coils which will be described presently. 70

The superheating coils are also of spiral form, like the coils 2, being located below 75 said coils 2 around the drum 1 and above the coils 11. The coils of the superheater are superposed and arranged in pairs. The inner and outer ends of the uppermost pair of coils 23 are connected, which is also true 80 of the next lower pair of coils 24, and the uppermost coils 23 and 24 of the two pairs are connected by an upstanding loop 25. The pair of superheater coils 26 below the coils 24 are similarly connected at their 85 outer and inner ends, and the uppermost coil 24 is connected to the uppermost coil 26 by an upstanding loop 27, said loop being at the inside of the coils while the loop 25 is on the outside. The inner and outer ends of 90 the lowermost pair of coils 28 are also connected, and the uppermost coils 26 and 28 of the respective pairs are connected on the exterior by an upstanding loop 29. The steam delivery pipe 30 is connected to 95 the uppermost coil 28 and delivers the steam from the boiler. In this arrangement, the uppermost coils of the several pairs are connected in series between the pipe 19 and the steam delivery pipe 30, while the lowermost coils of the several pairs are connected at their inner and outer ends to the corresponding ends of the respective coils of the pairs. Any water passing to the superheater will therefore flow downwardly into the 100 lower coils of the several pairs to be again generated into steam, while the steam will flow from the pipe 19 through the uppermost coils 23, 24, 25, and 26 into the pipe 30. The loops 25, 27 and 29 connecting the 105 coils will serve as traps to prevent water from gravitating downwardly from one coil to the other, thereby trapping any water in the lower coils of the pairs in which the water will remain until again generated into 110 steam, it being noted that the lower coils of the pairs are connected at both their inner and outer ends to the coils above them, whereby any water will flow downwardly 115 into the lower coils of the pairs. The dry steam can thus pass through the upper coils of the pairs and will be superheated and any water flowing into the lower coils of the pairs will be again transformed into steam and superheated to pass out with the steam delivered from the boiler. The steam is only passed through the superheater when the throttle valve 22 is opened, thereby retaining the steam in the storage coils until 120 needed, and in passing from the storage 125 coils will be superheated to pass out with the steam delivered from the boiler. The steam is only passed through the superheater when the throttle valve 22 is opened, thereby retaining the steam in the storage coils until 130 needed, and in passing from the storage

chamber to the superheater will be raised in temperature to the desired degree before being discharged from the boiler.

- Attention is directed to the fact that the 5 large "rib" pipes 17 extend from the "back bone" stand pipe 7 to the header 18 resembling the breast bone of the human body, providing a skeleton storage chamber of 10 large capacity surrounding the coils 2 and 15 superheater coils. This provides a substantial and efficient arrangement, the generating coils 11 being at the bottom, the superheater coils above them, and the economizer or water heating coils 2 at the top, with the 20 reserve coils surrounding the upper sets of spiral coils to keep the reserve steam heated by the products of combustion which pass upwardly within the skeleton storage chamber. 25 In the superheater, it will be noted that the lowermost coil of each pair is connected in parallel with its mate above it, so that the several pairs of superheating coils are connected in multiple (parallel with one another) with respect to the steam passage, and in series, the coils of each pair being 30 parallel with one another and in series with the other pairs of coils, whereby the upper coil of each pair carries the steam, while the lower coil of each pair receives the water and regenerates it into steam.

Figs. 10, 11 and 12 illustrate a modification in the connections of the generating coils to the drum 1'. Thus, the inner ends 35 12' of the generating coils are connected in a spiral series to the drum at the different sides thereof, and the baffle 13' is of annular or tubular form with radial partitions 14' between said tubular baffle 13' and the wall 40 of the drum 1', thereby separating the separator passage into vertical channels, the lower and upper ends of which are open. An annular deflector 15' carried by the wall of drum overhangs the upper end of the baffle 45 13' for directing water and steam downwardly within the baffle, so that the particles of water will be directed back into the water in the lower portion of the drum, while the steam can rise around the inner edge of the deflector to pass upwardly to the pipe 16. The water delivery pipe 5' extends downwardly centrally within the baffle 13'.

Having thus described the invention, what is claimed as new is:—

- 55 1. A boiler comprising a vertical drum, a stand pipe connected at its upper and lower ends with the upper and lower ends of the drum, respectively, generating coils in communication with the stand pipe and drum, a steam header, vertically spaced pipes connected to said stand pipe and header and constituting therewith a steam storage chamber, and a steam pipe connected to the header. 60

- 65 2. A boiler comprising a vertical drum, a

stand pipe connected at its upper and lower ends with the upper and lower ends of the drum, respectively, generating coils in communication with the stand pipe and drum, a steam header, vertically spaced pipes connected to said stand pipe and header and constituting therewith a steam storage chamber, and a steam pipe connected to the header, said vertically spaced pipes being inclined to drain any water therein back to the stand pipe. 70

3. A boiler comprising a central vertical drum, a stand pipe at one side of the drum and connected at its upper and lower ends to the upper and lower ends of the drum, respectively, generating coils surrounding the lower portion of the drum and communicating with the lower portion of the stand pipe and connected to the drum, a steam header at another side of the drum, vertically spaced pipes connecting said header and upper portion of the stand pipe and constituting therewith a steam chamber surrounding the drum, said vertically spaced pipes being inclined to drain any water 80 therein back to the stand pipe, and a steam pipe connected to the header for conducting the steam from said chamber. 85

4. A boiler comprising a central vertical drum, a stand pipe at one side of the drum and connected at its upper and lower ends to the upper and lower ends of the drum, respectively, generating coils surrounding the lower portion of the drum and communicating with the lower portion of the stand pipe and connected to the drum, a steam header at another side of the drum, vertically spaced pipes connecting said header and upper portion of the stand pipe and constituting therewith a steam chamber surrounding the drum, said vertically spaced pipes being inclined to drain any water 90 therein back to the stand pipe, and a steam pipe connected to the header for conducting the steam from said chamber. 95

100 5. A boiler comprising a vertical drum, a stand pipe at one side thereof having its lower end connected to the lower end of the drum, generating coils in communication with the stand pipe and drum, a steam chamber surrounding the drum, said chamber and upper portions of the stand pipe and drum being 105 connected for communication with one another, said chamber including a vertical header and vertically spaced pipes connecting said header and stand pipe, and a steam outlet pipe extending into the header and having branches extending into some of said vertically spaced pipes. 110

115 6. A boiler comprising a vertical drum, a stand pipe communicating at its upper and lower ends with the upper and lower end 120

125

245

1,550,942

5

- portions of the drum, respectively, generating coils in communication with said drum and stand pipe for receiving water and discharging water and steam into the drum, 5 a water heating coil surrounding the drum and delivering water to the lower portions of said drum and stand pipe, steam heating coils surrounding the drum above the generating coils, and a steam reserve chamber 10 surrounding the water heating and steam coils and connected to said stand pipe above the generating coils, said steam coils being in communication with said chamber.
7. A boiler comprising steam generating 15 means having an upper portion for steam and a lower portion for water, an annular steam reserve chamber surrounding said upper portion of said means and connected thereto for receiving steam therefrom, a 20 stand pipe having its upper terminal connected to said chamber and its lower terminal connected to the lower portion of said means for the return of water from said chamber to said lower portion, and a steam 25 coil connected to said chamber to receive steam therefrom and located between said chamber and upper portion of said means.
8. A boiler comprising a vertical drum, a stand pipe at one side thereof, generating 30 coils surrounding the lower portion of the drum, and a steam chamber composed of spaced pipes of skeleton form surrounding the upper portion of the drum, the generating coils, drum and stand pipe being connected for the circulation of water through the coils and lower portion of the drum, and the steam chamber and upper portions of the drum and stand pipe being connected for the flow of steam from the drum into said 35 chamber and for the return of water from said chamber into the lower portion of the stand pipe.
9. A boiler comprising a vertical drum, a stand pipe at one side thereof, generating 40 coils surrounding the lower portion of the drum, a steam chamber surrounding the upper portion of the drum, said generating coils, drum and stand pipe being connected for the circulation of water through said 45 coils and lower portion of the drum, the steam chamber and upper portions of the drum and stand pipe being connected for the flow of steam from the drum into said chamber and for the return of water from said chamber into the lower portion of the stand pipe, and a steam pipe connected to said 50 steam chamber at a different side of the drum than the stand pipe so that the steam must flow around said chamber from the 55 chamber into the lower portion of the stand pipe, and a steam pipe connected to said steam chamber at a different side of the drum than the stand pipe so that the steam must flow around said chamber from the 60 stand pipe to enter the steam pipe.
10. A boiler comprising a vertical drum, a stand pipe at one side thereof, generating coils surrounding the lower portion of the drum, a steam chamber surrounding the upper portion of the drum, said generating 65
- coils, drum and stand pipe being connected for the circulation of water through said coils, and lower portion of the drum, the steam chamber and upper portions of the drum and stand pipe being connected for the flow of steam from the drum into said chamber and for the return of water from said chamber into the lower portion of the stand pipe, and a steam coil surrounding the upper end of the drum between the drum and steam chamber and above the generating coils and connected to said chamber at a different side thereof than the stand pipe. 70
11. A boiler comprising a vertical drum, a stand pipe at one side thereof, generating 75 coils surrounding the lower portion of the drum, a steam chamber composed of spaced pipes of skeleton form surrounding the upper portion of the drum, and steam coils between the drum and steam chamber above the generating coils, said generating coils, drum and stand pipe being connected for the circulation of water through the generating coils and lower portion of the drum, and the steam chamber, steam coils and upper portions of the drum and stand pipe being connected for the flow of steam from the drum into said chamber for the return of water from said chamber into the lower portion of the stand pipe, and for the flow of steam from said chamber into the steam coils. 80
12. A boiler comprising a vertical drum, a stand pipe at one side thereof, generating 85 coils surrounding the lower portion of the drum, an annular steam chamber composed of spaced pipes of skeleton form surrounding the upper portion of the drum, steam coils above the generating coils between the drum and steam chamber, the generating coils, drum and stand pipe being connected for the circulation of water through said generating coils and lower portion of the drum, said chamber and upper portions of the drum and stand pipe being connected for the flow of steam from the drum into the chamber and for the return of water from said chamber to the lower portion of the stand pipe, and said chamber and steam 90 coils being connected at a different side of the drum than the stand pipe, and a water heating coil above the generating coils between the drum and steam chamber and communicating with the lower portions of the drum and stand pipe. 95
13. A boiler comprising a vertical drum, a stand pipe at one side thereof, generating 100 coils surrounding the lower portion of the drum, an annular steam chamber composed of spaced pipes of skeleton form surrounding the drum above the generating coils, steam coils and water heating coils above the generating coils surrounding the drum and located between the drum and said chamber, the generating coils, drum and 105
- 110

- 120
- 125
- 130

stand pipe being connected for the circulation of water through the generating coils and lower portion of the drum, the drum, steam chamber, upper portion of the stand pipe and for the flow of steam from said chamber into the steam coils, and the water heating coils being connected to the lower portions of the drum and stand pipe.

5 pipe and steam coils being connected for the flow of steam from the drum into said chamber, for the return of water from said chamber into the lower portion of the stand pipe

In testimony whereof we have signed our names to this specification.

HARTLEY O. BAKER.
CARLETON A. ORR.
